(57) **CLAIM**

The ornamental design for a pipe tong, as shown and described.

DESCRIPTION

FIG. 1 is a front top right perspective view of a pipe tong according to one embodiment of the invention, shown in a first position.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a front top right perspective view of the pipe tong of FIG. 1, shown in a second position.

FIG. 9 is a front view thereof.

FIG. 10 is a rear view thereof.

FIG. 11 is a front top right perspective view of another embodiment of the invention, shown in a first position.

FIG. 12 is a front view thereof.

FIG. 13 is a rear view thereof.

FIG. 14 is a right side view thereof.

FIG. 15 is a left side view thereof.

FIG. 16 is a top view thereof.

FIG. 17 is a bottom view thereof.

FIG. 18 is a front top right perspective view of the PIPE TONG of FIG. 11, shown in a second position.

FIG. 19 is a front view thereof; and,

FIG. 20 is a rear view thereof.

The broken lines in the figures show portions of the pipe tong which form no part of the claimed design.

1 Claim, 18 Drawing Sheets
